UNITED STATES PATENT OFFICE

WILLIAM B. SMALL, OF RACINE, WISCONSIN

WRENCH

Application filed November 3, 1930. Serial No. 493,021.

The invention relates to wrenches, and more particularly to wrenches of the geared type for use in locations inaccessible by wrenches of conventional construction.

5 The removal of the valve stem nuts from automobile wire wheels of the larger sizes, and the replacement of these nuts, have heretofore been awkward and tedious operations, because of the limited space available for the 10 use of tools. The usual types of close quarter wrenches have been found unsuitable for this service, and for this reason cold chisels have been commonly used for removing and replacing the nuts, with liability of damage 15 to the wheels.

It is an object of the present invention to provide a close quarter wrench of simple, durable, and inexpensive construction, which is well adapted for this service although capable of general use.

Another object of the invention is to provide a wrench which includes a detachable annular nut-receiving socket capable of being easily slipped over the valve stem of a tire 25 on a wire wheel even though the valve stem is fairly close to the adjacent spokes, and which has a detachable gearing connection with an easily removable driving handle, the device being so constructed that the nut may 30 be driven with the valve stem extending through the socket.

A further object of the invention is to provide a wrench of this character in which the geared parts of the wrench are retained in 35 their operative position by spring means, which also serves to hold a handle member in operative position.

A further object of the invention is to perfect details of the construction generally.

40 The invention further consists in the several features hereinafter set forth and more particularly defined by the annexed claims.

In the accompanying drawings, Fig. 1 is 45 a side elevation of a wrench embodying the invention, as it appears when used on a valve stem nut of a tire-carrying wire wheel, parts of the wheel and tire being shown in section;

Fig. 2 is a longitudinal sectional view of 50 the wrench taken along the line 2-2 of Fig. 1;

Fig. 3 is a fragmentary view of the wrench as it appears ready to receive the nut-driving socket member thereon, parts being broken away and parts being shown in section, and

Fig. 4 is a bottom view of the wrench with 55 the socket member removed and in position to receive this member.

In these drawings, the numeral 10 designates the rim of a wire wheel provided with the usual spokes 11 and carrying a tire casing 12 in which an inner tube 13 is enclosed. The inner tube 13 carries a bent valve stem 14, which is provided with the usual threaded shank receiving a nut 15. The laterally projecting portion of the valve stem extends between the spokes 11, which are usually in close proximity thereto.

The wrench of this invention includes an annular socket member 16 which is adapted to be slipped over the bent valve stem 14 and 60 has a polygonal recess 17 to receive the nut 15. Above the recess 17, the socket member is provided with a large cylindrical bore 18, so as to reduce the radial thickness of the socket member to a minimum consistent with 65 requirements of strength. In this manner, the socket member can be easily slipped over the bent valve stem 14 and may assume various positions eccentric to the stem for permitting the socket member to pass the closely 70 spaced spokes 11, which are usually in crossed relation in the vicinity of the valve stem.

The socket member 16 is provided at the edge opposite the recess 17 with gear teeth forming a bevel gear 19. This gear meshes 75 with a bevel gear 20 formed on the end of a tubular shaft 21, the gear 20 being preferably, although not necessarily, smaller than the gear 19. The tubular shaft 21 is provided with a shouldered bore 22 receiving 80 therein a shouldered rod 23 on which the shaft is journalled and slidably mounted. The tubular shaft 21 is also journalled in a bearing member 24 against which the gear 20 has an axial thrust, the bearing member 85 and tubular shaft being retained against relative axial movement by a pin 25 secured in the bearing member and entering an annular groove 26 formed about the shaft. The lower end of the bearing member 24 carries 90

a hook 27 having a curved edge portion bearing against a shoulder 28 formed about the socket member 16 to retain the meshed gears against movement along the axis of the socket member.

5 The end of the rod 23 adjacent the gear 20 is fixedly secured to an upstanding ear 29 of a fork member 30 which is provided with a cylindrical outer surface rotatably 10 fitting in the bore 18 of the socket member 16. The upper end of the ear 29 fixedly carries a pin 31, which extends in parallel relation to the axis of the shaft 21 and is slidably received in an apertured upper portion of 15 the bearing member 24, thus retaining the fork member 30 and the bearing member 24 against relative rotation while permitting their relative axial displacement. Near its outer end, the rod 23 is provided with an 20 annular rib 32 which is spaced outwardly from the end of the tubular shaft 21 to receive between them a compressed coiled spring 33 surrounding the rod 23, as seen in Fig. 2. An exteriorly knurled tubular 25 handle sleeve 34 encloses the spring 33 and at its inner end portion slidably fits about the tubular shaft 21. Near its outer end, the handle sleeve 34 is provided with an inwardly shouldered portion 35 slidably receiving therethrough the outer end portion of the rod 23 and bearing against the rib 32. Near its inner end, the tubular handle 30 sleeve 34 has a detachable connection with the tubular shaft 31 consisting, in the present instance, of a bayonet slot 36 in the handle sleeve receiving a screw 37 threaded radially into the tubular shaft 21. The coiled spring 33 thus not only urges the ear 29 of the fork member 30 toward the gear 20, 35 but also retains the handle sleeve in position. The handle sleeve may be readily removed from the tubular shaft 21 and be replaced by a longer sleeve in the event that this is made necessary by the work at hand.

40 After the socket member is applied to the valve stem nut in the manner heretofore described, it is ready to receive its complementary operating device. To apply the operating device, the fork member 30 is urged 45 away from the bearing member 24, as indicated in Figs. 3 and 4, and this is done either by holding the tubular handle sleeve in the hand and pushing the pin 31 with the thumb of the hand, or by holding the handle sleeve 50 in the fingers and pushing the palm of the hand against the protruding outer end of the rod 23. The fork member 30 is then free to be passed between the spokes of the wheel to straddle the threaded portion of the valve 55 stem and to be entered into the bore 18 of the socket member. After such entry, the tubular shaft 21 is released to permit the spring 33 to urge the gear 20 into mesh with the gear, and to simultaneously place the hooked end 27 60 of the bearing member 24 against the shoul-

der 28 of the socket member. The nut 15 is then rotated by turning the handle sleeve 34 on its axis to back the nut away from the rim. The nut may be thus rotated until it is released from the threaded portion of the valve 70 stem, or after a few turns of the nut, the driving device may be released from the socket member and the nut spun off with the fingers. In either case, the handle sleeve is removed from the socket member to permit the 75 socket member and the nut to be slipped off the bent portion of the valve stem. If the nut engages the rim so tightly that it cannot be loosened by rotating the handle sleeve on its own axis, the nut may be readily loosened by swinging the handle sleeve as a lever about the axis of the socket member, prior to the rotation of the handle sleeve on its own axis. When the handle sleeve is to be released from the socket member, it is only necessary to back off the gear 20 from the gear 19, simultaneously with the release of the hook 27 from the shoulder 28, thus permitting the fork member 30 to be lifted out of the bore 18 in the cylindrical member and 80 withdrawn laterally from the valve stem.

85 When the nut is to be replaced on the valve stem, it is slipped over the bent portion of the valve stem of the threaded shank thereof, and following this the socket member 16 is 90 also slipped over the valve stem, in the manner heretofore described. The driving device is then engaged with the socket member by the manipulation above noted for effecting the rotation of the nut.

95 The spring 33 serves to retain the handle assembly firmly in driving engagement with the socket member, but this assembly is easily and single-handedly releasable therefrom. During the use of the device, there 100 is a slight outward axial thrust on the gear 20, but this thrust is effectively resisted by the spring 33.

105 While close quarter wrenches including gearing connections have heretofore been devised, and particularly wrenches embodying bevel gears, such wrenches have been unsuitable for operations of the type herein contemplated, especially where the threaded member extends a considerable distance 110 through the nut. Although the wrench of the present invention is particularly adapted for use with valve stem nuts, it will be obvious that the device is not restricted to such use.

115 When nuts of different sizes are to be manipulated by the wrench, it is only necessary to substitute other socket members for attachment to the same operating device. In some instances, an adapter may be inserted 120 in the socket member for handling a smaller nut.

125 What I claim as new and desire to secure by Letters Patent is:

130 1. A wrench comprising a rotatable wrench

element, a gear carried on said element, a guide member releasably journaled in said element and disposed substantially co-axially of said element, a rod carried by said guide member, a tubular shaft journaled on said rod, a gear carried on said tubular shaft and releasably meshing with said first-named gear, spring means for urging said last-named gear toward said guide member, and 5 a retaining member carried on said tubular shaft and having a releasable connection with exterior portions of said wrench element for retaining said gears in meshing engagement.

2. A wrench comprising an annular socket member adapted to receive a nut therein and adapted to receive a threaded nut-carrying member therethrough, a gear carried on said socket member, a forked guide member releasably journaled in said socket member 20 and disposed substantially co-axially of said socket member, said forked guide member being adapted to straddle said threaded member and being laterally removable therefrom, a gear operatively connected to said guide member and releasably meshing with said first gear, handle means for rotating said second gear, and means for releasably retaining said gears in meshing engagement.

3. A wrench comprising a rotatable wrench element, a gear on said element, a second gear releasably meshing with said first gear, means for rotating said second gear, a pair of members releasably and slidably engaging the inner and outer surfaces of said 35 wrench element for relative rotation therewith, and means for supporting and retaining said last-named members in assembled relation when said wrench element is withdrawn from said members.

4. A wrench comprising a rotatable wrench element having an exterior shoulder, a guide member releasably journaled in said element, a gear on said element, a second gear releasably meshing with said first gear, a 45 retaining member operatively connected with said second gear and having a laterally separable engagement with the shoulder of said wrench element for retaining said gears in meshing engagement, and means for rotating said second gear.

5. A wrench comprising a rotatable wrench element, a gear carried on said element, a second gear releasably meshing with said first gear, a shaft carrying said second gear, a pair 55 of relatively movable members engageable with said wrench element for retaining said gears in meshing engagement, spring means acting on said shaft for retaining said last-named members in operative position with respect to said wrench element, and a handle sleeve surrounding said spring means and secured to said shaft.

6. A wrench comprising a rotatable wrench element, a gear carried on said element, a 65 second gear releasably meshing with said first

gear, a shaft carrying said second gear, a guide member releasably journaled in said wrench element, a rod carried on said guide member and passing through said shaft, a spring surrounding said rod and acting on said shaft to urge said gears into meshing engagement, and a retaining member carried on said shaft and releasably engageable with the exterior portion of said wrench element.

7. A wrench comprising an annular socket member adapted to receive a nut therein and to receive a threaded nut-carrying member therethrough, a guide member removably journaled in said socket member and having an axially disposed recess receiving an intermediate portion of said threaded member therethrough, a gear carried on said socket member, a second gear releasably meshing with said first-named gear and rotatable on an axis angularly spaced from the axis of said socket member, and means carried on said guide member for supporting said second gear.

8. A wrench comprising a rotatable wrench element, a gear on said element, driving means for said gear including a second gear releasably meshing with said first gear, and a pair of relatively movable retaining members carried on said driving means and releasably engageable with said wrench element for confining said gears in meshing engagement, one of said retaining members being laterally separable from said wrench element.

9. A wrench comprising a rotatable wrench element, a gear on said element, driving means for said gear including a second gear releasably meshing with said first gear, a pair of relatively movable retaining members carried on said driving means and releasably engageable with said wrench element for confining said gears in meshing engagement, and spring means for holding said retaining members in operative engagement with said wrench element.

10. A wrench comprising a rotatable wrench element having an exterior shoulder, a gear on said element, a second gear releasably meshing with said first gear, means for retaining said gears in meshing engagement including a member having a laterally separable engagement with the shoulder of said wrench element, and means for rotating said second gear.

In testimony whereof, I affix my signature.

WILLIAM B. SMALL.
